United States Patent

Des. 239,426

Patented Apr. 6, 1976

239,426

STAND FOR POTTED PLANTS

William D. Bailey, Box 26, Woodleaf, N.C. 27054

Filed Nov. 6, 1974, Ser. No. 521,411

Term of patent 14 years

Int. Cl. D6—06; D11—02

U.S. Cl. D6—85

FIG. 3

FIG. 4

FIG. 2

FIG. 1

FIG. 1 is a perspective view of a stand for potted plants showing my new design, the pots being shown in broken lines for illustrative purposes only;

FIG. 2 is a front elevational view;

FIG. 3 is a top plan view; and

FIG. 4 is a bottom plan view.

I claim:

The ornamental design for a stand for potted plants, as shown and described.
